UNITED STATES PATENT OFFICE.

WALTER C. MAGEE AND WALLACE M. COX, OF NEW YORK, N. Y., ASSIGNEES
TO WILLIAM JAMES HOGG & SON, OF WORCESTER, MASSACHUSETTS.

DESIGN FOR CARPET.

SPECIFICATION forming part of Design No. 27,004, dated April 27, 1897.

Application filed March 10, 1897. Serial No. 626,896. Term of patent 3½ years.

To all whom it may concern:

Be it known that we, WALTER C. MAGEE and WALLACE M. COX, citizens of the United States, residing at New York, in the county of New York and State of New York, have invented and produced a new and original Design for Carpets, of which the following is a specification.

Our invention relates to a design to be worked into or upon carpeting or similar fabrics; and we do hereby declare that the drawing accompanying this specification gives and conveys to any one skilled in the art of carpet-weaving a clear understanding of the same that is sufficient to enable such persons to use our invention.

The said drawing is a face view of a carpet embodying our new design.

The drawing illustrates a body and a border.

- o The body A consists of a substantially uniform groundwork upon which appear ornamental cross-shaped figures formed by interlacing curved lines, crossing so as to produce a star-shaped figure at the center of each.
- 5 The figures are placed diagonally as to each other. Between these appear other figures of

the general shape of a Greek cross, having a circle at their centers.

The border B consists of a groundwork and figures of the same general character and arrangement as the body. The outer edge is characterized by rows of jagged points and ornamental figures resembling conventionalized buds.

The colors employed for the different portions of this design may be varied to suit the convenience or taste of the manufacturer.

What we claim, and desire to secure by Letters Patent, is—

1. In a design for carpeting, the body A, substantially as shown.
2. In a design for carpeting, the border B, substantially as shown.
3. The design for carpets, consisting of the body A and the border B, substantially as shown.

WALTER C. MAGEE.
WALLACE M. COX.
